Inventor:

Arthur Lipschutz
By Wright, Brt atty's.

UNITED STATES PATENT OFFICE.

ARTHUR LIPSCHUTZ, OF ST. LOUIS, MISSOURI.

BRAKE-JAW FOR CAR-BRAKE RODS.

SPECIFICATION forming part of Letters Patent No. 733,853, dated July 14, 1903.

Application filed January 19, 1903. Serial No. 139,626. (No model.)

To all whom it may concern:

Be it known that I, ARTHUR LIPSCHUTZ, a citizen of the United States, residing in the city of St. Louis, in the State of Missouri, have invented certain new and useful Improvements in Brake-Jaws for Car-Brake Rods, of which the following is a full, clear, and exact description, reference being had to the accompanying drawings, forming part 10 of this specification.

The object of my invention is to provide a jaw to which the brake-rod can be attached in a more secure, convenient, and economical manner than heretofore, as well as in 15 less time and without requiring the use of special tools.

My invention consists in features of novelty hereinafter fully described, and pointed out in the claims.

20 Figure I is a perspective view of my brake-beam jaw. Fig. II is a longitudinal vertical section of the jaw, showing the adjacent end of the brake-rod with its extremity turned down in the act of applying the rod to the 25 jaw. Fig. III is a like view showing the extremity of the rod bent around the web of the jaw, which position it assumes when the rod is fully attached to the jaw. Fig. IV is a horizontal section taken on line IV IV, Fig. III.

30 Referring to the drawings, 1 represents the jaw, that is preferably in the form of a casting of either steel or malleable iron. It has a longitudinal opening 2, that receives the brake-lever, which I have not shown. The 35 inner end of the jaw is provided with the usual opening 3 to receive the bolt that connects the jaw to the brake-lever. At the outer end of the opening 2 the jaw has a vertical wall 4 to receive any inward thrust of 40 the brake-rod, and beyond this wall is a vertical opening 5 to receive the end of the brake-rod 6. Between the opening 5 and the end of the jaw is a web 7, that is preferably of less thickness than the jaw, thereby forming 45 a groove 8, in which the brake-rod is embedded when its end has been bent around the web, as shown in Fig. III.

To attach the rod to the jaw it is only necessary to bend its end at right angles to its

length and then insert it into the opening 5, 50 as shown in Fig. II, and then by the use of an ordinary hammer to bend the extremity of the rod around the web into the position shown in Fig. III. This attachment of the rod to the jaw can be effected without heating the former and can be very quickly accomplished without the use of any special tools, which are often not at hand when a brake-rod becomes broken and a new one has to be applied. The work can be quickly 60 and economically accomplished, and when the job is done it is of a substantial and permanent character, and the rod is held from longitudinal movement with relation to the jaw when the brakes are operated. 65

The opening or perforation 5 extends vertically through the jaw or in the same direction as the opening 3, so that a central draft or pull of the rod on the jaw is provided for, and by passing the bent end of the rod through 70 the opening 5 from the top there is no tendency of the rod to drop away from the jaw while its extremity is being bent around the web or in case of any straightening out of the bent portion of the rod. 75

I claim as my invention—

1. A brake-jaw for car-brake rods, having a perforation or opening at its outer end, through which the brake-rod is adapted to pass, and having a web beyond the opening 80 about which the extremity of the rod is adapted to be bent, substantially as set forth.

2. A brake-jaw for car-brake rods having a perforation in its outer end through which the brake-rod is adapted to pass, a wall forward of said perforation, and a web back of said perforation about which the extremity of the rod is adapted to be bent, substantially as set forth. 85

3. A brake-jaw for car-brake rods having 90 a perforation or opening at its outer end through which the brake-rod is adapted to be passed, and having a web beyond said opening of less thickness than the jaw, whereby a groove is formed to receive the rod when the latter is bent around the web, substantially 95 as set forth.

4. A cast brake-jaw for car-brake rods, hav-

ing an opening to receive the brake-lever, and a perforation at its inner end to receive the connecting-bolt; the outer end of said jaw being formed with an opening extending in the same direction as said bolt-opening, and which is adapted to receive the end of the brake-rod and having a web beyond said open-

ing about which the brake-rod is adapted to be bent, substantially as set forth.

ARTHUR LIPSCHUTZ.
